UNITED STATES PATENT OFFICE.

CHARLES A. REULE, OF CINCINNATI, OHIO.

BELT-BUCKLE.

1,346,795.

Specification of Letters Patent. Patented July 13, 1920.

Application filed March 20, 1920. Serial No. 367,345.

To all whom it may concern:

Be it known that I, CHARLES A. REULE, a citizen of the United States, residing at Cincinnati, in the county of Hamilton and State of Ohio, have invented certain new and useful Improvements in Belt-Buckles, of which the following is a specification.

This invention relates to certain new and useful improvements in belt buckles and the primary object of the invention is to provide a buckle of this type with means, such as a hook which engages a front belt loop on the trousers and holds the belt against movement.

15 The invention further aims to provide means which is of simple and economical construction, reliable and effective in operation and which is devoid of any movable parts subject to derangement and requiring 20 special manipulation.

In the drawings:—

Figure 1, is a front side elevation of a buckle equipped with the present invention: Fig. 2 is a top plan view, and

25 Fig. 3 is a rear elevation, partly in section.

In proceeding in accordance with the present invention, the type of buckle represented in the drawings may vary and be 30 of any desired form, for example same may have a front plate or body 1; a cam type of pin clamp 2 and a pivoted bail 3, one end of the belt being permanently affixed to the bail while the other end is adjustably held 35 by the cam pin or roller 2.

The invention resides in the provision of a hook 4 of approximately U-form and which may be constructed of a piece of wire or strip of metal. The free end 5 of the hook is spaced below the top flange 6 of the 40 face or front plate, while the opposite end of leg 7 of the hook is extended above end 5 and terminates in a right angular part 8, which latter is rigidly secured to the under face of flange 6 in any suitable manner. 45 The entire hook structure is spaced from the front plate 1 of the buckle so that the trousers loop L can be engaged between the hook and plate 1 and by the ends 5 and 7 of the hook.

50 As shown in Fig. 3, the loop L, which is of fabric is sewed at its lower end to the front of the trousers T, so that the free upper end of the loop can be easily engaged with the hook as depicted in Fig. 3.

55 What is claimed is:

1. In a belt buckle, a front plate having a top flange, and a hook rigidly secured to the flange and depending therefrom, said hook being spaced from the front plate and 60 having one end spaced below the flange.

2. In a belt buckle, a front plate having a top flange, and a hook of U-form having one end free and spaced below the flange and having its other end formed with a 65 lateral extension secured to the under face of the flange, the hook being spaced from the front plate.

In testimony whereof I affix my signature.

CHARLES A. REULE.
